DESIGN FOR A HAT

Samuel Scheuer, New York, N. Y.

Application May 24, 1935, Serial No. 56,995

Term of patent 3½ years

To all whom it may concern:

Be it known that I, Samuel Scheuer, a citizen of the United States of America, residing in Manhattan, county of New York, and State of New York, have invented a new, original, and ornamental Design for a Hat, of which the following is a specification, reference being had to the accompanying drawing, forming part thereof, wherein,

I claim:

The ornamental design for a hat, substantially as shown.

SAMUEL SCHEUER.
